CONTAINER

Benjamin M. Williams, St. Louis, Mo., assignor to
 Gaylord Container Corporation, St. Louis, Mo.,
 a corporation of Maryland

Application March 3, 1944, Serial No. 524,855

3 Claims.

(Cl. 229—35)

This invention relates to containers, particularly shipping cartons of the kind having a body and a cover with tongues for locking the cover to the body. The principal object of the present invention is to provide a slip cover of the above type having a strong and durable end wall construction including a locking tongue and readily accessible means for disengaging the locking tongue from the body. The invention consists in the carton and in the construction, combinations and arrangements of parts hereinafter described and claimed.

In the accompanying drawings, which form part of this specification and wherein like symbols refer to like parts wherever they occur,

Fig. 1 is a side elevational view of a carton embodying my invention.

Fig. 2 is an end elevational view of said carton.

Fig. 3 is a perspective view of the body of the carton.

Fig. 4 is a fragmentary perspective view of the slip cover of the carton.

Fig. 5 is a vertical cross-sectional view through the slip cover on the line 5—5 in Fig. 4.

Fig. 6 is an enlarged vertical cross-sectional view on the line 6—6 in Fig. 2.

Fig. 7 is a plan view of the blank from which the cover is made; and

Figs. 8 and 9 are fragmentary perspective views showing the cover in process of erection.

In the accompanying drawings, my invention is shown embodied in a shipping carton comprising a body A and a slip cover B, both made of corrugated board, fiberboard or other bendable material. The body A preferably comprises a bottom wall 1 with upstanding end flaps 2 and upstanding side walls 3 with end flaps 4 that are bent inwardly and suitably interlocked with the bottom wall flaps to form two-ply end walls. The upstanding bottom wall flaps 2 have hand holes 5 cut therethrough; and the inturned side wall flaps 4 have tabs 6 that cover said hand holes and cooperate with the portions of the bottom wall flaps thereabove to provide spaces or pockets for cover locking tongues hereinafter described. The side wall flaps 4 are scored, as at 7, above the hand holes 5 so that the tabs 6 are adapted to swing inwardly away from said hand holes. The body A is shown and described in detail in my copending application Serial No. 524,854 filed concurrently herewith.

As shown in Fig. 7, the blank from which the slip cover B is constructed is divided by longitudinal score lines 8 and transverse score lines 9 into a top wall panel 10 with end flaps 11 and

two side wall panels 12 with end flaps 13 that are of a length more than half the width of said top wall and are each notched, as at 15, the notch in one flap being in its outer edge and the notch in the other flap being in its inner edge. The end flaps 11 of the top wall panel 10 are folded along score lines 16 that extend from end to end of said flaps midway of the free outer edges thereof and the score lines 9. The outer portions of the end flaps 11 have U-shaped slits 17 cut therein, and the portions defined by these slits are adapted to be folded along the score lines 16 to form locking tongues 18 and to leave openings 19 in the portions of the flaps vacated by said tongues. As shown in the drawing, the tongues 18 may have parallel slits 20 therein midway of their side edges, said slits extending from score lines 21 formed in said tongues between their free edges and the score lines 16 and extending across the latter into the inner portions of the end flaps 11 where they are connected by cross slits 20a so as to provide pull tabs 22 for said tongues.

The slip cover B is set up or erected by first folding the side wall panels 12 upwardly along the score lines 8 and then bending the end flaps 13 thereof inwardly along the score lines 9 into overlapped and interlocked relation by extending each flap through the notch 15 in the other flap. The end flaps 11 of the top wall panel 10 are then bent upwardly along the score lines 9 outside of the interlocked end flaps 13 of the side walls and are thence rebent along the score lines 16 against the inner sides of said interlocked end flaps, the inturned portions of the flaps 11 fitting snugly between the sides 12 so as to be held in place by friction. The openings 19 vacated by the locking tongues 18 are of greater width than the width of the overlap of the interlocked end portions of the side wall flaps 13, thereby permitting relatively close contact between the inturned portions of the top wall flaps 11 and the portions of the side wall flaps between the overlapped portions thereof and the side walls 12.

By the arrangement described, the slip cover B, with the locking tongues 18 depending therefrom, is slipped over the top of the body B and is quickly and easily locked thereto by bending said locking tongues along the score lines 16 inwardly through the hand holes 5 and thence along the score lines 21 upwardly around the upper edges of said holes and between the bottom wall flaps 2 and side wall flaps 4 of said body. When it is desired to unlock the cover B, the exposed free outer ends of the pull tabs 22 of the tucked-in locking tongues 18 are grasped by the fingers and

pulled outwardly, thereby pulling said tongues downwardly from their tucked-in position between the inner and outer plies of the end walls of the body and thence outwardly through the hand holes 5 therein. The slip cover B may be quickly and easily set up; and the cooperating end flaps 11 and 13 provide end walls that are strong and rigid despite the portions that are cut from the flaps 11 to form the cover locking tongues 18.

What I claim is:

1. A carton comprising a body and a cover therefor, said body having a wall with a hand hole therethrough, and said cover having a corresponding wall with a locking flap that is bent inwardly through said hand hole into said body, the cover wall and said locking flap being slit to provide a relatively long pull tab that is bent inwardly with said locking flap through said hand hole and is anchored to the portion of said locking flap located in said body and terminates in an exterior free end portion that is disconnectable from said cover wall for withdrawing said locking flap from said hand hole.

2. A carton comprising a body and a cover therefor, said body having two-ply end walls with hand holes through the outer plies only thereof, and said cover having end walls with locking tongues depending therefrom that are bent inwardly through said hand holes and have their free end portions bent upwardly around the upper edges thereof and tucked between the inner and outer plies of said two-ply end walls, the end walls of said cover and said locking tongues being

slit to provide pull tabs that are connected to the upwardly tucked-in portions of said tongues and extend from said tucked-in portions outwardly through said hand holes where they terminate in free end portions that are disconnectable from said end walls of said cover for withdrawing said tucked-in portions of said tongues from between said inner and outer plies and through said hand holes.

3. A carton comprising a body and a slip cover therefor, said body having end walls with hand holes therein, said cover comprising a top wall having end flaps and depending side walls having end flaps that are bent inwardly with their end portions overlapped and interlocked, the end flaps of said top wall being folded downwardly outside of said overlapped side wall flaps and thence upwardly around the lower edges thereof and along the inner sides thereof, the upwardly folded portions of said end flaps of said top wall being cut out to provide locking tongues that are bent inwardly through said hand holes and thence upwardly inside said body, said locking tongues being cut out to provide pull tabs thereon that are bent inwardly and upwardly with said locking tongues and terminate in exposed free outer ends that are accessible from the exterior of said carton for withdrawing said locking tongues from said hand holes, the cut outs in the upwardly folded portions of said end flaps of said top wall being wide enough to accommodate the overlapped and interlocked end portions of the in-turned side wall flaps.

BENJAMIN M. WILLIAMS.
